UNITED STATES PATENT OFFICE.

MELBOURNE W. WHITE, OF LYNN, MASSACHUSETTS, ASSIGNOR TO UNITED SHOE MACHINERY CORPORATION, OF PATERSON, NEW JERSEY, A CORPORATION OF NEW JERSEY.

LINING-TRIMMING MACHINE.

1,415,967.

Specification of Letters Patent. Patented May 16, 1922.

Application filed August 1, 1919, Serial No. 314,698. Renewed August 19, 1921. Serial No. 493,700.

To all whom it may concern:

Be it known that I, MELBOURNE W. WHITE, a citizen of the United States, residing at Lynn, in the county of Essex and 5 State of Massachusetts, have invented certain Improvements in Lining-Trimming Machines, of which the following description, in connection with the accompanying drawings, is a specification, like reference characters 10 on the drawings indicating like parts in the several figures.

This invention relates to cutting machines and is herein illustrated as embodied in a machine designed to trim the lining which 15 projects from the top of a shoe.

In the manufacture of certain kinds of footwear, such for example as pumps and rubber overshoes, it is customary to provide a lining which projects more or less above 20 the upper edge of the piece. In the case of pumps, the lining is commonly one of leather, and the projecting portion is tacked to a last. In the case of rubber overshoes, a fabric lining is commonly drawn over the 25 top of a form. In either case the lining fits snugly about the last or form and serves to prevent the upper edge of the piece of footwear from bulging away from the last or form, particularly at the arch portion 30 thereof. After all the operations which are to be performed while the piece of footwear is on its last or form have been completed, the piece is removed, and the projecting portion of the lining trimmed off.

35 Machines which have been provided for performing this operation have been found more satisfactory in operating upon pumps, said machines comprising a cutter to which the pump is fed by hand, the pump being 40 grasped and pushed forward in proper relation to the cutter. A shoe of this kind is comparatively rigid, the curves in its upper edge are commonly not abrupt and the leather lining is comparatively stiff, so that 45 the procedure outlined above is perfectly practicable. With a rubber overshoe such a procedure is not so satisfactory owing to the extreme flexibility of rubber and to the fact that very sharply curved edges are frequently 50 encountered. To push a rubber overshoe forward against a cutter is practically impossible, and to pull it is objectionable because of the facility with which rubber is stretched. It is also difficult to 55 guide such a piece of work and at the same time feed it.

According to one feature of the present invention, means are provided for feeding the upper edge of the shoe to the cutter so that flexible shoes such as rubber overshoes 60 as well as more rigid kinds of footwear may readily be operated upon. In the illustrative machine the work is fed intermittently over a support to the cutter by feed mechanism which grips the work close to the cutter. 65 This construction not only ensures that the flexible material shall be firmly held at the locality in which the cutting operation is taking place but leaves the operator free to concentrate all his effort and attention on 70 the proper guiding of the work.

In trimming such a projecting lining as has been referred to above, the entire upper edge of the shoe is fed over the support, the shoe being turned and swung in various directions during the operation. In order to provide space for such movements of the shoe, another feature of the invention relates to the mounting of the instrumentalities which engage the shoe, including the 80 support, the cutter and the feeding means upon an overhanging arm so that a free and unobstructed space is provided about these members in which the shoe may readily be manipulated.

These and other features of the invention, including certain details of construction and combinations of parts will be described as embodied in an illustrative machine and pointed out in the appended claims.

Referring now to the accompanying drawings, —

Fig. 1 is an elevation of a machine in which the present invention is embodied;

Fig. 2 is a vertical longitudinal section 95 on the line 2—2 of Fig. 3;

Fig. 3 is a section on the line 3—3 of Fig. 2;

Fig. 4 is a section on the line 4—4 of Fig. 3, and

Fig. 5 is a section on the line 5—5 of Fig. 1.

Referring first to Figs. 1 and 5, the base 7 of the machine is provided at one end with casters 9 so that by tipping the machine 105 slightly it may be readily moved from place to place in the factory such a capability being especially desirable in a factory in which rubber footwear is being made. The base, near the end at which the casters are located, 110 has an upright socket to receive a pedestal 11 which has a series of holes 13 in any one

of which may be placed a pin 15, the socket being split and having lugs to receive pinch-bolts 17. The pedestal may thus be held in adjusted position. Near the end of the base 5 remote from the casters is a second upright socket in which is mounted in a manner like that of the pedestal 11, a smaller pedestal 18 having at its upper end a seat 19. At the upper end of the pedestal 11 is an overhanging arm 21 at the outer end of which are mounted the instrumentalities for engaging the work; and on the base 7 below the seat 19 are two treadles 23 and 25 which are connected with cables 27 and 29, the cable 27 10 running over an idler 31 and being connected at its upper end to a presser-lifting lever 33, and the cable 29 running over an idler 35 and being connected at its upper end to a lever 37 which controls a friction clutch. 15 Any suitable clutch mechanism may be used, and the present one will not be described further than to say that depression of the treadle 25 pulls the left-hand end of the lever 37 downwardly against the force of the spring 39 and connects the driving shaft, 20 presently to be referred to, with a continuously driven pulley 41 on the shaft of a motor 43. With this construction it is possible to adjust the machine to the stature of 25 the operator and to move it about in the factory. In the manufacture of rubber overshoes, it is commonly the custom to pile the over-shoes, which have been removed from the vulcanizer, on long tables; and the 30 present machine is particularly designed to be moved from place to place along these tables.

Referring now more particularly to the remaining figures, a driving shaft 45 is 40 mounted in the overhanging arm and has at its outer end a cam 47, from which, as will presently appear, the feed member and cutter are operated. Extending from the lower portion of the downwardly turned end of the 45 arm 21 is a bracket 49 to the lower end of which is fastened a work support 51, the fastening consisting of a screw 53 extending through a slot in the support and threaded into the bracket, so that the support may be 50 adjusted horizontally. Formed integral with the support 51 is a stationary shear blade 55; and extending up through a slot in the support is a feed member 57 the operative face of which is inclined to the horizontal in a plane which is always parallel to or coincident with the plane of the operative inclined surface of the work support. It should be noted in this connection that the upper surface of the shear blade 55 is part of 55 the inclined operative surface of the work support. The feed member is adjustably fastened to a lever 59 by a cap screw 61 which passes through a slot in the feed member and is threaded into the lever. This 60 lever at its upper end is hung on the cam 47

and between its ends has a hub through which extends a pivot pin 63. The pin has an enlarged head at its left-hand end, as viewed in Fig. 2, formed with a bore extending vertically through it, and in this bore is 70 adjustably fastened, by set screw 65, the stem of a knife-holder 67, this stem passing up through alined bores formed in a plate or cover 69 which is fastened to the overhanging arm 21 by screws 71. As best 75 shown in Fig. 3, the upper end of the lever 59 is generally L-shaped and the arms of the L are connected by an angle iron 73, the whole forming a sort of box in which the cam 47 is located. When, therefore, the 80 shaft 45 is rotated, the lever is both oscillated about the pivot 63 and moved up and down with said pivot, such movements imparting to the feed member 57 a four-motion feed movement to feed the work intermittently over the support.

At the lower end of the knife holder is fastened a knife 75 located to co-operate with the shear blade 55, and held from springing away from the blade by a leaf-spring 77. It will now be seen that by loosening the screw 53, the work support, and with it the shear blade, may be adjusted to bring the shear blade into proper position with respect to the knife. It has been explained above that the stem of the knife-holder 67 serves as a guide for the vertical movement of the pivot pin 63. In performing this function it is of course reciprocated; and the construction and arrangement of 90 parts is such that the knife is brought down to sever the work during the pauses in the intermittent feed movements. As an additional guide for the vertical movement of the pivot pin 63 a roller 78, carried at one 95 end of the pin, runs between guides formed in the down-turned portion of the arm 21.

In order to hold the work upon the work support so as to permit it to be fed properly, an idle presser wheel 79 is rotatably mounted on an arm 81 and held in place by a nut and washer. This wheel is preferably made of soapstone to prevent the work from sticking to it and thereby interfering with the feed. By referring to Fig. 4 it will be seen that the 105 feed member 57 engages the lining 100 and that the presser engages the rubber 200. Rubber overshoes, as has been mentioned, are vulcanized in the course of their manufacture, and for some time after they come 110 out of the vulcanizer are warm enough to be sticky. While in this condition a steel presser wheel will stick to them more or less, but by using a soapstone wheel this 115 tendency to stick is avoided. The flat face of the presser wheel which is nearest the knife may in some cases serve, by engagement with the underside of the bead 300, as a guide for the work. In the piece of work shown in 120 Fig. 4, the bead is too narrow to permit the 125 130

flat face of the presser wheel which is shown to be so used. In order to facilitate guiding of the work irrespective of the width of the bead, the lower end 5 of the arm 81 is formed as a gage 83 which extends over into engagement with the upper side of the bead. It is desirable at times to swing the presser and gage up out of the way; and to permit such swinging the upper end of the arm 81 is pivoted at 10 85 between the arms of a yoke 87, the upper end of the arm having formed therein two notches about ninety degrees apart with either of which a spring-pressed pin 89 may 15 co-operate. In Fig. 2 the arm 81 is shown in broken lines in its raised position. The stem 91 of the yoke 87 extends up through a lower bearing formed in the plate or cover 69 and into a bearing in a hollow adjusting 20 nut 93 threaded into the plate. Between the lower end of the nut and a shoulder on the stem is a coiled spring 95 which holds the presser down against the work. In order to facilitate raising of the presser when desired, a horizontal stud 97 carried by the 25 stem of the yoke 87 is engaged on its under side by a lifter in the form of a lever 99 which is pivoted to the overhanging arm at 101 and is attached at its remote end to the 30 cable 27. A spring 103 normally holds the lever in the position shown. When the pedestal is raised or lowered the cables 27, 29 may be lengthened or shortened by readjusting the clamps 105.

35 The rubber overshoes as they come to this machine have been removed from the last or form, this removal having been preceded by slitting the projecting lining, usually at the back of the overshoe, from the upper edge 40 of the overshoe through the top of the lining. The operator takes the overshoe in this condition, depresses the treadle 23 to permit the upper margin of the overshoe to be placed properly on the support 51 with the gage 83 45 in contact with the upper side of the bead 300. He then releases the treadle 23, depresses the treadle 25 to start the machine, and guides the work as it is fed.

50 Although the invention has been described with reference to trimming the projecting lining of rubber footwear and as embodied in a particular machine, it should be understood that the invention is not limited in the scope of its application to any particular 55 kind of work or to the machine which has been shown and described.

In order to promote brevity, the word "shoe," as used in the appended claims, is intended to cover broadly various kinds of 60 footwear such as shoes proper and overshoes, whether made of rubber, leather or other material, since obviously the operation of the machine is not affected by the character of the piece of footwear which is presented 65 to it.

Having thus described my invention, what I claim as new and desire to secure by Letters Patent of the United States is:

1. A machine for trimming the lining which projects from the top of a shoe, having 70 in combination, a support for the upper edge of the shoe, means for feeding the upper edge over the support, and means for severing the lining close to said edge.

2. A machine for trimming the lining 75 which projects from the top of a shoe, having in combination, a support for the upper edge of the shoe, means for feeding the upper edge intermittently over the support, and means for severing the lining close to said 80 edge.

3. A machine for trimming the lining which projects from the top of a shoe, having in combination, a support adapted to enter 85 the shoe so as to support the upper edge thereof, a cutter, means for operating the cutter to sever the lining on an angle to the operative face of the support, and means for feeding the upper edge of the shoe over the support. 90

4. A machine for trimming the lining which projects from the top of a shoe, having in combination, a support adapted to enter 95 the shoe so as to support the upper and lining at the top of the shoe, said support having a shear blade, a cutter, means for causing the cutter to co-operate with the shear blade to sever the lining, means for guiding the top of the shoe in such manner as to bring the lining into the path of the cutter at a 100 locality close to the edge of the upper, and means for feeding the top of the shoe over the support.

5. A machine for trimming the lining which projects from the top of a shoe, having 105 in combination, a support for the shoe, a cutter, means for operating the cutter to sever the lining, a feed member adapted to engage the lining, a presser co-operating with the feed member, means for guiding 110 the top of the shoe in such manner as to bring the lining into the path of the cutter at a locality close to the edge of the upper, and means for operating the feed member to advance the lining to the cutter. 115

6. A machine for trimming the lining which projects from the top of a shoe, having in combination, a support for the shoe, a cutter, means for operating the cutter to sever the lining, a feed member projecting 120 through the support into engagement with the lining, a presser co-operating with the feed member, means for guiding the top of the shoe in such manner as to bring the lining into the path of the cutter at a locality close 125 to the edge of the upper, and means for operating the feed member to advance the lining to the cutter.

7. A machine for trimming the lining which projects from the top of a shoe, having 130

- in combination, a support shaped to enter the shoe and to support the upper margin thereof, a presser for holding the upper edge of the shoe against the support, a cutter, means for causing the cutter to sever the lining, a guide arranged to engage the edge of the upper, and means for feeding the upper edge of the shoe over the support to present the projecting lining to the cutter.
- 10 8. A machine for trimming the lining which projects from the top of a shoe, having in combination, a support shaped to enter the shoe and to support the upper margin thereof, a presser for holding the upper edge of the shoe against the support, a cutter, means for guiding the shoe in such manner as to cause the cutter to sever the lining close to the edge of the upper, and means for feeding the upper margin of the shoe intermittently over the support to present the projecting lining to the cutter.
- 15 9. A machine for trimming the lining which projects from the top of a shoe, having in combination, a support shaped to enter the shoe and to support the upper margin thereof, said support having a shear blade, a presser for holding the upper margin of the shoe against the support, a guide for the top of the upper, means for causing the cutter to co-operate with the shear blade to sever the lining, and means for feeding the upper margin of the shoe over the support.
- 20 10. A machine of the class described, having in combination, an overhanging arm, having a depending portion, a work support, a presser, a cutter and a feed member all mounted on the depending portion of the arm, and means for operating the cutter and feed member.
- 25 11. A machine of the class described, having in combination, a frame having an overhanging arm provided with a depending portion, a work support mounted on the depending portion, a feed member mounted on the depending portion and arranged to engage the under side of the work, a presser and a cutter also mounted on the depending portion, and means for operating the feed member and cutter.
- 30 12. A machine of the class described, having in combination, a work support, feeding means including a carrier movable toward and from the support, and a knife-holder mounted in the carrier.
- 35 13. A machine of the class described, having in combination, a work support, a feed member, a carrier upon which the feed member is pivoted, means for reciprocating the carrier and for swinging the feed member about the pivot, and a knife-holder fast to the carrier.
- 40 14. A machine of the class described, having in combination, a work support, a feed member, a carrier upon which the feed member is pivoted, means for reciprocating the

carrier and for swinging the feed member about the pivot, and a knife holder fast to the carrier, the knife holder serving to guide the carrier in its reciprocating movement.

15. In a machine for trimming the lining which projects from the top of a shoe, having in combination, a work support, a cutter, and a shear blade mounted on the work support in position to co-operate with the cutter, said work support being adjustable to maintain the proper relation between the cutter and shear blade.

16. A machine for trimming the lining which projects from the top of a shoe, having in combination, a work support, a cutter, and a shear blade mounted on the work support in position to co-operate with the cutter, said work support being adjustable to maintain the proper relation between the cutter and shear blade, a feed member extending up through the support adjacent to the shear blade, and means for operating the feed member.

17. A machine for trimming the lining which projects from the top of a shoe, having in combination, a support for the upper edge of the shoe, a cutter for severing the lining, a presser co-operating with the support, a gage for the upper of the shoe, and a bracket upon which both the presser and the gage are mounted.

18. A machine for trimming the lining which projects from the top of a shoe, having in combination, a support for the upper edge of the shoe, a cutter for severing the lining, a presser co-operating with the support, a gage for the upper of the shoe, and a bracket upon which both the presser and the gage are mounted, said bracket being pivoted on the frame of the machine to permit the presser and gage to be swung together out of the field of operation.

19. A machine for trimming the lining which projects from the top of a shoe, having in combination, a support for the upper edge of the shoe, a cutter for severing the lining, a presser co-operating with the support, a gage for the upper of the shoe, a bracket upon which both the presser and gage are mounted, and means for raising and lowering the bracket to facilitate presentation of the work to the machine.

20. A machine of the class described, having in combination, a work support, a tool for operating upon the work, a presser for holding the work on the support, an edge gage, a bracket on which the presser and the gage are mounted, a carrier to which the bracket is pivoted, and means for raising and lowering the carrier.

21. A machine for trimming the lining which projects from the top of a rubber overshoe, having in combination, a support adapted to enter the shoe, a cutter for severing the projecting lining, and means for

feeding the top of the shoe over the support, said means including a feed member adapted to engage the lining near the top of the shoe and a soapstone presser adapted to engage 5 the rubber at a locality opposite to the locality in the lining which is engaged by the feed member.

22. A machine for trimming the lining which projects from the top of a shoe, having 10 in combination, a support for the upper edge of a shoe, a cutter, means for causing the cutter to move in a path which is inclined to the surface of the support, and means for feeding the top of the shoe and

for guiding it in such manner that the lining is severed on an angle close to the edge of the upper. 15

23. A machine for trimming the lining which projects from the top of a shoe, having in combination, a support for the upper 20 edge of a shoe, a cutter, means for operating the cutter, and means for feeding the top of the shoe and for guiding it in such manner that the lining is severed on an angle close to the edge of the upper. 25

In testimony whereof I have signed my name to this specification.

MELBOURNE W. WHITE.
